UNITED STATES PATENT OFFICE.

CHRISTIAN WILLIAM MEINECKE, OF JERSEY CITY, NEW JERSEY.

DESIGN FOR A BOTTLE.

SPECIFICATION forming part of Design No. 20,376, dated December 9, 1890.

Application filed October 31, 1890. Serial No. 369,982. Term of patent 7 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for Polygonal Bottles, of which the following is a specification.

This invention relates to a design for a bottle serviceable for holding such substances as perfumes, oils, or other liquids of a similar nature.

The bottle may be made of any suitable material, such as glass, porcelain, or clay; and the design is illustrated in the accompanying drawing, which shows a perspective view of the bottle.

A is the body, polygonal in cross-section, having a raised band b at its lower end and a raised band c at its upper portion. Above

this band is formed a shoulder d, from which rises the cylindrical neck e. The shoulder d is sloping and dome-shaped from the neck e toward the upper band c.

What I claim as new, and desire to secure 25 by Letters Patent, is—

The design for a bottle, consisting of the polygonal body A, having the base-band b, the top band c, the shoulder d, extending from the top band, and the cylindrical neck 30 e, rising from the center of the shoulder, substantially as shown and described.

In testimony whereof I have hereunto set my hand in the presence of two subscribing witnesses.

CHRISTIAN WILLIAM MEINECKE.
